UNITED STATES PATENT OFFICE

HERBERT L. BONE, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRACK CIRCUITS

Application filed April 14, 1931. Serial No. 530,020.

My invention relates to railway track circuits, and particularly to track circuits which are used for locking a switch and thereby preventing the switch from being moved 5 while a car is passing through the switch.

The present invention is especially suitable for use in connection with the switches in freight classification yards. The minimum spacing between cars which are being classified in such yards is determined by the length of the switch detector track circuit, and the greater the spacing between cars, the slower is the operation of the yard. It is desirable, therefore, to keep the detector track circuits 10 as short as possible.

The conventional freight car has a wheel base of 37 feet or less, and the spacing between the inner wheels of the two trucks is about 27 feet. It follows that for conventional freight cars, a track circuit 27 ft. long will prevent the switch from being thrown between the trucks of a car. Special steel cars are being built at the present time, however, for the handling of structural steel, 20 and the spacing between the inner wheels of the two trucks of these cars is approximately 54 ft. It follows that for these special cars a track circuit 54 ft. long is required in order to prevent the switch being thrown between 25 the trucks.

One feature of my invention is the provision of a track circuit which will operate to release the switch as soon as the rear wheels of the conventional freight car have passed 30 the switch, but which will function to prevent the switch being thrown between the trucks of the special steel cars hereinbefore referred to.

I will describe one form of track circuit 35 embodying my invention, and will then point out the novel features thereof in claims.

The accompanying drawing is a diagrammatic view showing one form of track circuit embodying my invention.

Referring to the drawing, the reference characters 1 and 1^a designate the track rails of a railway track, which rails are connected with the rails 10 and 10^a of a branch track by a switch S. The rail 1^a is divided by insulated joints 2 to form an insulated section

A—B, the point A being located immediately in advance of the switch S. The rail 1 is divided by similar joints to form a section C—D. The two sections A—B and C—D are staggered, but overlap. For example, the length of each section may be 54 ft., and the length of the overlapping portions between the points A and D may be 27 ft. A source of track circuit current 3 is connected from the right-hand end of section A—B to the right-hand end of section C—D, a current limiting resistance 4 being interposed between these rails and the rail 1. A track relay 5 is connected from the left-hand end of section A—B to the left-hand end of section C—D. It is understood that the relay 5 controls the switch S in the usual and well known manner, so that the switch cannot be moved unless the relay is energized.

Preferably, the rail 1 is provided with an auxiliary section D—F, the point F being located opposite the point B, and the rail 1^a is provided with a similar auxiliary section E—A, the point E being located opposite the point C. The only purpose of these auxiliary sections is to eliminate the effect of any stray current which might pass through the track rails and interfere with the proper functioning of the track circuit if the insulated joints 2 were not provided at points E and F.

The rails 10 and 10^a of the branch track are tied into the track circuit for the rails 1 and 1^a in the usual manner.

Assuming that a conventional freight car moving toward the left, passes through the track circuit, it will be seen that this car has no effect on the track relay until the first pair of wheels passes the point D. The relay will then be shunted and will remain shunted until the last pair of wheels passes the point A. Relay 5 will then immediately become energized. That is to say, the spacing between the inner wheels of the two trucks of the car is less than the distance between points A and D, so that while the car is passing through the track circuit, it can not bridge the portion of track between these two points.

When a special steel car passes through

the track circuit, it will, likewise, have no effect until the first wheels pass the point D, whereupon, the relay 5 will be shunted. After the forward truck passes the point A, 5 there will be an interval of time during which there are no wheels of the car between points A and D, but during this time one truck will be between points E and A, and the other truck will be between points D 10 and F. During this time relay 5 will still be shunted, because there will be a complete path of low resistance from the left-hand terminal of the relay through the rail 1, the forward truck, the steel body of the car, the 15 rear truck of the car, and the rail 1^a, to the right-hand terminal of relay 5. The resistance of this path will be sufficiently low to keep the relay 5 deenergized. As soon as the rear wheels of the car pass the point A, relay 20 5 will again become energized to release the switch S.

It follows that by means of a track circuit embodying my invention, it is impossible to throw the switch S under either the conventional freight car or the special steel freight car, and yet the track circuit places no limitation on the spacing of the cars passing through the classification yard.

Although I have herein shown and described only one form of track circuit embodying my invention, it is understood that various changes and modifications may be made therein within the scope of the appended claims without departing from the spirit and scope of my invention.

Having thus described my invention, what I claim is:

1. A railway switch detector track circuit comprising staggered insulated sections in 40 the two track rails overlapping by an amount greater than the distance between the inner wheels of the two trucks of a standard freight car but less than the distance between the inner wheels of the two trucks 45 of a special steel freight car, a source of current connected across said sections at one end, and a track relay connected across said sections at the other end.

2. A railway switch detector track circuit 50 comprising staggered but overlapping main insulated sections in the two track rails, an auxiliary insulated section in each rail extending from the associated main section to a point opposite the end of the main section 55 in the other rail, a source of current connected across said main sections at one end, and a track relay connected across said main sections at the other end.

In testimony whereof I affix my signature.
